[57] CLAIM

The ornamental design for a combined cab and hood
for a loader vehicle, as shown.

DESCRIPTION

FIG. 1 is a top, right side perspective view of a com-
bined cab and hood for a loader vehicle showing my
new design, it being understood that the broken lines
are for illustrative purposes only;

FIG. 2 is a front elevational view thereof;

FIG. 3 is a left side elevational view thereof; and

FIG. 4 is a rear elevational view thereof.
